THUMB HOLE STRUCTURE FOR BOWLING BALLS

Romeo G. Lerro and Joseph V. Urbano,
Newark, N. J.

Application October 16, 1951, Serial No. 251,612

3 Claims. (Cl. 273—63)

1

This invention relates to improvements in bowling balls, and has reference, more particularly, to improvements in the means by which the ball is gripped when delivering the same upon a bowling alley in play.

In the common type of bowling ball, the grip thereof comprises a thumb hole and one or more finger holes, all of which enter the body of the ball, and which are relatively spaced to receive the thumb and finger or fingers of the hand by which the ball is manipulated.

Most bowlers seek to impart a twist or spin to the ball at the moment of delivery of the same onto the alley. In so doing use is made of the thumb as the pivot or center about which the leverage of the fingers, in imparting a twist to the ball, is exerted, whereby to initiate spinning movement of the ball to accompany its rolling progress down the alley, thus inducing the ball to follow a curving trajectory. Such manipulation of the ball not only puts considerable strain upon the thumb, but causes a twisting of the thumb in the thumb hole, and consequent strong frictional rubbing of the thumb against the wall surface of the thumb hole. By reason of this, the bowler's thumb frequently becomes irritated and sore, with risk of development of blisters and painful callouses; all of which interferes with and frequently prevents desired control of the ball when delivering the same onto the alley. In addition to this, the twisting of the thumb in the thumb hole is likely to cause such spreading or distortion of the thumb as to result in jamming and sticking of the same within the thumb hole at the moment of ball delivery, so that frictional resistance to release of the ball from the hand occurs, which interferes with timing, speed and directional accuracy of ball delivery.

Having the above objectionable effects in view, it is the primary object of this invention to provide a thumb hole structure for a bowling ball, which avoids said effects; and, to this end, to provide the ball with a freely rotatable element imbedded therein in which the thumb hole is formed. The thumb hole element being freely rotatable about the axis of the thumb hole, said element quickly responds to and follows twisting or turning movements of the thumb, so that no frictional rubbing of the thumb against the wall surface of the thumb hole can occur, and no spreading or distortion of the thumb is induced which would be likely to cause jamming or sticking thereof in the thumb hole, and consequently the thumb easily withdraws from the thumb hole without frictional check or impedance of such withdrawing movement as it leaves the bowler's hand, thus assuring better control of

2

the ball for properly timed delivery thereof with directional accuracy at desired speed.

Other objects and advantages of the invention will appear as the following specific description thereof is read in connection with the accompanying drawings, in which:

Fig. 1 is an elevational view of a bowling ball showing the grip thereof which includes the freely rotatable thumb hole element according to this invention.

Fig. 2 is an elevational view in part section with the freely rotatable thumb hole element shown in longitudinal vertical section.

Fig. 3 is a fragmentary sectional view showing a modified form of the freely rotatable thumb hole element.

Similar characters of reference are employed in the aforesaid views, to indicate corresponding parts.

20 Referring to Figs. 1 and 2, the body of the bowling ball is indicated by the reference character 10. Entering the ball body 10 are finger holes 11, and in suitably spaced relation thereto is positioned a freely rotatable thumb hole element.

25 The ball body is provided with a radial bore or socket 12 which terminates at its outer end in a diametrically enlarged annular seat 13 outwardly open at the surface of the ball body. Housed in the bore or socket 12, so as to be rotatable therein about its longitudinal axis, is a cylindrical rotatable element 14. Said element 14 is provided at its outer end portion, preferably as an integral part thereof, with an external annular flange or head 15, which lies within the outwardly open portion of the annular seat 13, and is diametrically sized to loosely fit within the embrace of the side walls of the latter. The outer end surface of the element 14 together with the outer face of the flange or head 15 are convexly curved to flushly conform to the surface curvature of the ball body 10. Extending longitudinally into the element 14 is a thumb receiving hole 16.

30 The flange or head 15 of the element 14 is of less thickness than the depth of the annular seat 13, thus providing an annular chamber intermediate the underside of said flange or head 15 and the bottom of the annular seat 13 for the reception of an anti-friction bearing by which the element 14 is supported for unimpeded rotation about its longitudinal axis.

35 In a preferred form thereof, the anti-friction bearing is of the ball bearing type, and comprises an outer race member 17 and an inner race member 18 with an annular row of ball bearings 19 engaged in and between the race grooves or channels with which the opposed inner

faces of the race members are provided. The outer race member 17 is seated within the annular seat 13 in forced fit and therefore fixed engagement with the side walls of the latter, whereby to be secured to and unitary with the ball body 10. The inner race member 18 is engaged around the element 14 beneath its flange or head 15 in forced fit and therefore fixed engagement therewith, whereby to be secured thereto so as to be unitary therewith. The outer race member being unitary with the ball body and the inner race member being unitary with the element 14, the annular row of ball bearings 19 engaged in and between the race member grooves or channels not only assure free, unlimited and unimpeded rotative movement of the element 14 in swiveling relation to the ball body 10, but also act as keys between the ball body and said element adapted to secure the latter within the former against outward axial displacement from its operative assembled relation thereto. It will be noted that the ball bearing is thus located relative to the outer end portion of the element 14 where, in the use of the ball, maximum thrusting pressure of the bowler's thumb is exerted. By reason of this, tendency of the element 14 to cant in the socket 12, with risk of frictionally impeding its free rotation is avoided.

From the above it will be obvious that the thumb hole element 14 is capable of free, unlimited and unimpeded rotation in swiveling relation to the ball body, and consequently, when engaged by the inserted thumb of the bowler's ball manipulating hand, will follow any turning movement of the thumb resulting from manipulation of the ball for delivery thereof onto the alley. Since the thumb hole element thus freely rotates in response to thumb movement, all frictional rubbing of the thumb against the wall surface of the thumb hole 16 is prevented, and twisting or distortion of the thumb by contact with an immovable thumb hole surface, with risk of jamming or sticking of the thumb in the thumb hole, is likewise avoided. It will, therefore, be understood that the bowler's thumb lies normally straight and free within the thumb hole throughout all phases of the delivery manipulation of the ball by the bowler, and, as the ball leaves the hand upon delivery, the thumb will quickly withdraw from the thumb hole without frictional resistance to such withdrawing movement. Due to these advantages, the bowler will maintain desired control of the ball during all phases of delivery manipulation thereof, so that accurate delivery placement, with induced spin if desired, is better attained, and this without risk of irritation of the thumb likely to result in soreness or formation of blisters or callouses.

Some bowlers prefer to have the thumb hole of the ball somewhat oblique to the radius of the ball body. In such case, as shown in Fig. 3, the freely rotatable thumb hole element 14 according to this invention may be modified to provide a thumb hole oblique to its longitudinal axis at a selected angular degree. To this end, the rotatable element 14 is provided with a longitudinal bore 20 for the reception of an adapter piece 21 in which is formed a thumb hole 22 of selected oblique angularity. Said adapter piece 21 is engaged in the bore 20 of element 14 with a press or force fit so as to be thus secured in unitary relation thereto, whereby to turn therewith. In other respects the modified construction of Fig. 3 is the same as that of the previously described construction shown in Figs. 1 and 2.

Having now described our invention, we claim:

1. In a bowling ball, a thumb hole structure imbedded radially therein in spaced span determining relation to the finger hole grip portion of the ball, said structure comprising a rotatable cylindrical element provided with a thumb receiving opening extending axially thereto, and a ball-bearing comprising an outer race member immovably affixed to the ball body, an inner race member immovably affixed to the rotatable element and an annular row of anti-friction balls intermediate said race members to support said rotatable element for unlimited and unimpeded free rotation about its longitudinal axis and thus in swiveling relation to the ball body and to secure said element against axial displacement from operative assembled relation to said ball body.

2. A bowling ball having a socket extending radially into its body from the surface thereof, said socket terminating at its outer end in an outwardly open diametrically enlarged annular seat portion, said socket being located in spaced span determining relation to the finger hole grip portion of the ball, a thumb hole structure mounted in said socket, said thumb hole structure comprising a rotatable cylindrical element provided with a thumb receiving opening extending axially thereto, said element having an external annular head flange disposed within the outer open end of said annular seat portion of the socket flush with the surface of the ball body, and an anti-friction bearing housed within said annular seat portion of the socket beneath the head flange of said element, whereby to support said element for unlimited and unimpeded free rotation about its longitudinal axis and thus in swiveling relation to the ball body.

3. A bowling ball having a socket extending radially into its body from the surface thereof, said socket terminating at its outer end in an outwardly open diametrically enlarged annular seat portion, said socket being located in spaced span determining relation to the finger hole grip portion of the ball, a thumb hole structure mounted in said socket, said thumb hole structure comprising a rotatable cylindrical element provided with a thumb receiving opening extending axially thereto, said element having an external annular head flange disposed within the outer open end of said annular seat portion of the socket flush with the surface of the ball body, and a ball-bearing housed within the seat portion of said socket beneath the head flange of said element, said ball-bearing comprising an outer race member immovably affixed to the ball body, an inner race member immovably affixed to the element, and an annular row of anti-friction balls intermediate said race members to support said element for unlimited and unimpeded free rotation about its longitudinal axis and thus in swiveling relation to said ball body and to secure said element against axial displacement from operative assembled relation to said ball body.
